UNITED STATES PATENT OFFICE

172,863

SCREW CLAMPING DEVICE OR SIMILAR ARTICLE

Henry J. Buckley, Gardiner, Maine, assignor to
J. F. Hodgkins Company, Randolph, Maine, a
corporation

Application February 25, 1954, Serial No. 29,207

Term of patent 14 years

(Cl. D54—13)

To all whom it may concern:

Be it known that I, Henry J. Buckley, a citizen of the United States, residing at Gardiner, in the county of Kennebec, in the State of Maine, have invented a new, original, and ornamental Design for a Screw Clamping Device or Similar Article, of which the following is a specification, reference being had to the accompanying drawing, forming a part thereof, in which:

Figure 1 is a front elevational view of a screw clamping device embodying my new design.

Figure 2 is a side elevational view thereof, and

Figure 3 is a rear elevational view thereof.

I claim:

The ornamental design for a screw clamping device or similar article, substantially as shown.
